(57) **CLAIM**

The ornamental design for an Applicator for Pharmaceutical Preparation, as shown and described.

DESCRIPTION

FIG. 1 is a perspective view of an Applicator for Pharmaceutical Preparation embodying our design.

FIG. 2 is a front elevational view thereof.

FIG. 3 is a top plan view thereof.

FIG. 4 is a bottom plan view thereof.

FIG. 5 is a side elevational view thereof, showing the Applicator for Pharmaceutical Preparation rotated 90° from the elevational view in FIG. 2.

FIG. 6 is a cross-sectional view thereof, taken in the direction of line 6-6 in FIG. 2.

The broken lines depict portions of the Applicator for Pharmaceutical Preparations that form no part of the claimed design.
